UNITED STATES PATENT OFFICE.

JOSEPH MARX, OF HARTINGTON, NEBRASKA.

IGNITION SYSTEM FOR INTERNAL-COMBUSTION ENGINES.

1,084,096.

Specification of Letters Patent. Patented Jan. 13, 1914.

Application filed August 15, 1913. Serial No. 784,961.

To all whom it may concern:

Be it known that I, JOSEPH MARX, citizen of the United States, residing at Hartington, in the county of Cedar and State of Nebraska, have invented certain new and useful 5 Improvements in Ignition Systems for Internal-Combustion Engines, of which the following is a specification.

The present invention relates to a governor controlled ignition system for internal combustion engines, the object of the invention being to provide a device of this character which embodies novel features of construction whereby the time of sparking can 15 be changed and the tension upon the governor correspondingly regulated without the necessity of stopping the engine.

Further objects of the invention are to provide a governor controlled ignition system of this character which is comparatively 20 simple in its construction, which can be easily and quickly manipulated, and which enables the speed of the engine to be readily controlled by the operator.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:—

Figure 1 is a side elevation of an internal combustion engine provided with an ignition and speed controlling device constructed in accordance with the invention, portions being broken away. Fig. 2 is a top plan view 40 of the same, portions being broken away, and Fig. 3 is an enlarged detail view of the speed controlling lever, parts being shown in section.

Corresponding and like parts are referred 45 to in the following description and indicated in all the views of the drawings by the same reference characters.

Specifically describing the present embodiment of the invention, the character A designates an internal combustion engine of the conventional construction, the said engine including a bed 1, cylinder 2, crank shaft 3, and fly wheel 4. The cylinder 2 is provided 50 at one side thereof with a conventional make-igniter 5 provided with the usual trip arm 6. The end of the cylinder 2 is provided with

the spring seated exhaust valve 7 and the lever 8 for operating the same, the said lever being pivoted between its ends and one extremity thereof serving to open the exhaust 60 valve when the opposite end thereof is engaged by the end of the valve operating slide 9 upon the inward movement thereof.

The crank shaft 3 is provided with a pinion 10 which meshes with a gear wheel 11 65 upon a short counter-shaft 12, the said gear wheel being provided upon one side thereof with a cam 13 adapted to engage a roller 14 upon the end or nose of the valve operating slide 9 so that as the gear 11 rotates the said 70 slide 9 will be reciprocated back and forth. This operation of the valve operating slide 9 is so timed with reference to the movements of the piston within the engine cylinder as to open the exhaust valve 7 and permit a fresh 75 charge to enter the engine at proper intervals.

An ignition operating detent 15 is pivotally mounted upon the valve operating slide 9 at an intermediate point between its 80 ends, as indicated at 16, the nose of the detent projecting upwardly away from the slide 9 so as to engage the trip arm 6 of the igniter 5, while the opposite end of the detent is connected to a slide or sleeve 17 upon a 85 spark controlling slide 18, one end of which is formed with a curved extension 18^a which has a pin and slot connection 19 with the main lever 20. The opposite end of the spark controlling slide 18 is adapted to slide 90 upon an adjustable seat 21 and is provided with a cam portion 18^b adapted to coöperate with the rounded nose 21^a of the said seat 21 to raise and lower the spark controlling slide 95 as it is reciprocated back and forth by the main lever 20. Suitable guides 60 and 61 are provided for the slide 18.

The rear end of the adjustable seat 21 is hinged at 22 to a base plate 23 supported by the bracket 24. A set screw 25 passes 100 through the base plate 23 and engages the lower surface of the adjustable seat 21 so that through the medium of the set screw the adjustable seat can be swung upwardly or depressed as may be found desirable.

The end of the spark controlling slide 18 adjacent the main lever 20 passes through a guide 26 upon the frame 27 of the lever 20. With this construction it will be obvious that by manipulation of the lever 20 the spark 110 controlling slide 18 can be reciprocated longitudinally and that as the slide is thus

5 moved the cam portion 18 thereof will co-operate with the seat 21 to raise and lower the rear end of the slide and thereby operate through the sleeve 17 to adjust the ignition detent 15 upon the valve operating slide 9. This admits of the sparking being advanced by moving the main lever 20 away from the fly wheel 4 and toward the cylinder 2.

10 A governor 28 is mounted upon the crank shaft 3, the governor collar engaging one 15 end of a lever 29 which is pivotally mounted between its ends upon a suitable bracket at 30, the opposite end of the lever being provided with a curved nose 31 which is 20 adapted to engage a shoulder 32 upon the valve operating slide 9 to retain the said slide at the rear limit of its movement and out of the path of the cam 13 when the speed of the engine becomes excessive. The free 25 end of the governor lever 29 is connected by a link 33 to one arm of a bell crank lever 34, the opposite arm of the said bell crank being connected by a spring 35 to the main lever 20. This spring 35 is the only spring 30 which is embodied in the governor construction, and it will be apparent that the tension in this spring is increased as the main lever 20 is moved away from the fly wheel and toward the cylinder for the purpose of advancing the spark, as has been previously described.

35 The lever 20 is formed at one side thereof with a nose 36 adapted to engage the teeth 37 upon a segmental rack 38 upon the lever frame 27. The lever 30 is pivoted upon a bolt 39 and a spring 40 is applied to this bolt in such a manner as to retain the lever yielding in an upright position and thereby retain the nose 36 in a yielding engagement 40 with the teeth of the segmental rack.

45 When the main lever 20 is moved toward the fly wheel to the extreme end of the segmental rack 38, the engine is brought to a stop. In order to start the engine, the main lever 20 is moved a slight distance toward the cylinder so as to set the ignition system for a late spark and also place the spring 35 under sufficient tension to hold the nose 31 of the governor lever out of engagement 50 with the shoulder 32 of the valve operating slide 9. In order to increase the speed of the engine, the lever 20 is advanced along the rack 38 toward the cylinder 2, thereby advancing the spark and simultaneously increasing the tension of the spring 35. The 55 tension in this spring 35 controls the action of the governor 28, since the greater the tension in the spring, the more powerful must

be the action of the governor to overcome the tension of the spring and swing the governor lever 29 to bring the nose 31 into engagement with the shoulder 32 of the valve operating slide 9 and thereby prevent further operation of the slide until after the speed of the engine is decreased. With this construction the lever 20 can be moved so as to advance or retard the spark and simultaneously adjust the tension in the spring 35 in a corresponding manner, without the necessity of stopping the engine.

Having thus described the invention, what I claim as new and desire to secure by Letters Patent, is:—

1. A speed controlling device for internal combustion engines including an igniter, an exhaust valve operating rod, cam means for actuating the exhaust valve operating rod, an adjustable detent upon the same for actuating the igniter, a speed controlling lever, means actuated by the speed controlling lever for adjusting the detent to regulate the sparking, a governor, an operative connection between the governor and the valve operating rod, a lever having one end thereof connected to the governor mechanism, and a spring connecting the opposite end of the lever to the speed controlling lever whereby the tension of the spring will be increased when the speed controlling lever is moved to advance the spark.

2. A speed controlling device for internal combustion engines including an igniter, an exhaust valve operating rod, cam means for actuating the exhaust valve operating rod, an adjustable detent upon the same for actuating the igniter, a speed controlling lever, an operative connection between the speed controlling lever and the said adjustable detent, a springless governor, a governor lever provided with a nose adapted to engage a shoulder upon the valve operating rod, a lever pivoted between its ends and having one end thereof in connection with the governor lever, and a spring connecting the opposite end of the lever to the speed controlling lever, the said spring controlling the action of the governor and the tension of the spring being increased when the speed controlling lever is moved to advance the spark.

In testimony whereof I affix my signature in presence of two witnesses.

JOSEPH MARX.
